UNITED STATES PATENT OFFICE.

THOMAS W. SOWELL, OF DALLAS, TEXAS, ASSIGNOR TO THE PORTABLE REFINERY COMPANY, OF DALLAS, TEXAS, A CORPORATION OF DELAWARE.

PORTABLE REFINERY.

Application filed June 5, 1922. Serial No. 505,810.

This invention relates to new and useful improvements in portable refineries.

The object of the invention is to provide a crude oil refinery composed of a plurality of units, each of which is mounted on a railway car or other portable support, whereby it may be transported from one field to another, and the units connected so as to set up a crude oil refinery in a comparatively short time. An advantage of such an arrangement is that after the initial expense of construction, a crude oil refinery may be set up in a field within a few days at a comparatively small expense, and when said field becomes unprofitable for the operation of the refinery, the latter may be moved to another field at a comparatively small expense.

My invention contemplates making portable only those parts and units, which it would be profitable to transport and abandoning those parts and units which could be replaced at a cost less than the cost of removing.

Another object of the invention is to make certain upstanding parts readily removable so as to permit the units to pass under bridges and the like and to reduce top heaviness, so that the cars will not overturn on short curves.

A further object is to provide portable refinery units which will be complete in themselves and comprise the necessary elements to function effectively and economically, either separately or conjointly.

It is obvious that in making the units portable certain provisions must be made and it is not claimed as the invention, the mere portability of the units, but rather the means whereby the units are made portable. However an invention of this character permits of considerable variation in structure and while it is not intended to limit the invention to the hereinafter recited details of construction, there are certain features, which have been found to dominate in a portable refinery. Among these features are adequate bracing and staying, and suitable heat insulation.

A construction designed to carry out the invention will be hereinafter described together with other features of the invention.

The invention will be more readily understood from a reading of the following speci-

fication and by reference to the accompanying drawings, in which an example of the invention is shown and wherein:

Fig. 1 is a side elevation of the front half of a train including units and carriers involved in the carrying out of my invention,

Fig. 2 is a side elevation of the rear half of said train,

Fig. 3 is a perspective view of a refinery plant involving the portable units of my invention,

Fig. 4 is a side elevation of the shell still unit, portions being illustrated in section,

Fig. 5 is a plan view of the same,

Fig. 6 is a side elevation of the tube still unit,

Fig. 7 is a plan view of the same,

Fig. 8 is a transverse sectional view of the shell still unit,

Fig. 9 is an end elevation of the shell still unit,

Fig. 10 is an end elevation of the tube still unit,

Fig. 11 is a partial plan view of the second unit showing the expansion drum,

Fig. 12 is a detail of the screw joint of the dome,

Fig. 13 is a detail of the smoke stack joint,

Fig. 14 is a detail of the tower joint, and

Fig. 15 is a diagrammatical plan showing the means of connecting and

Figs. 16, 17, 18 and 19 are diagrammatic elevations showing the pipe connections between the units.

In the drawings the numerals 20 and 21 designate respectively a pipe or tube still unit and a shell still unit, which I prefer to mount upon railway flat cars, but which may be mounted on carriers of other types. Each flat car is of the usual construction, but in order to properly support the load and provide a means of attachment, the floor of the car is made up of a plate 22, which is preferably of steel and to which the superimposed elements of the refinery may be readily bolted. At one end of the plate is fastened a tube still 23 of any approved construction, the details of which form no part of the invention. In order to protect the car from the high temperature of the still while in operation, it is deemed expedient to place a layer or bottom 23' of heat insulation under the entire still. This layer may include well known heat insulating ma-

aterials to which may be added Portland cement to give it body and strength enough to resist all tendency in crumbling when the car is in transit or from shocks incidental to switching.

On the opposite end of the floor plate is mounted an elevated condenser box 24 containing the usual coils 25. The condenser box is mounted on uprights or columns 26, which latter are firmly secured to the floor plate 22. As is shown in Figs. 4, 6, 9 and 10 the condenser box is fastened in a cradle formed by the columns 26 and cross beams 28, the latter extending from the columns 26 on one side to those on the other side and supporting the bottom of the box. The columns extend up the sides of the box and heavy angle bars 27 fastened on top of said columns are secured longitudinally to the box.

The condenser box with its coils will be extremely heavy and therefore requires adequate bracing to prevent displacement. Along the inside of each row of columns is fastened an upright steel plate 29 extending from the floor plate 22 to the tops of the columns. These brace or side plates are firmly secured to the columns and the floor plate and the cross beams 28 have their ends secured to said side plates and are supported on angle brackets 28'. As an additional staying means inclined braces 30 extend down from the beams to plates as is best shown in Figs. 9 and 10.

The side plates with the bottom of the condenser box constitute a housing under said box. The ends of the housing are left open and port holes 31 with suitable closures are provided in the side plates. In order to properly support the coils in the condenser box and prevent shifting of the same due to impact, cross bars 32 are arranged in the box at each end of each coil as is shown in Figs. 4 and 6. Also as a supporting and bracing means, wood or other blocks 33 are disposed vertically and under the coils and shaped to fit the same. Wood or equivalent material is used to provide for expansion and contraction of the coils.

Within the housing under the condenser box I mount a pump 34 and an auxiliary pump 35, the latter to be used in emergencies. A suction pipe 36 through which the crude oil is admitted extends from the side of the central portion of the car and is connected with both of the pumps 34 and 35. A discharge pipe 37 leads forwardly from the pump 34 and a discharge pipe 37' leads forwardly from the pump 35 and each of these pipes includes a cut-off valve 38. The pipes just described are connected in a vertical pipe 39 which extends vertically and has its upper end connected with a three-way joint 40. From this joint a pipe 41 extends toward the still

23 and has its opposite end connected with said still by an angular pipe connection 42. A valve 36' is connected in the pipe 36 and alined with the valves 38 at the inner end of the box 24 so as to be easily accessible from the space between the still and the box.

The oil is pumped through the pipes 36, 37, 39, 41, and 42 into the still 23 where it is subjected to heat in the usual manner and is discharged from said still through a pipe 43 which is connected with a downwardly extending pipe 44 by means of a T 44'. The pipe 44 is connected at its lower end with a T 45 from which a pipe 46 extends into an expansion drum 47, the latter being mounted and securely fastened on the floor plate between the still and the box. The pipe 46 is turned upwardly in the drum and discharges the heated oil on to a baffle plate 48 within said drum whereby the vapors and hot gases are given an opportunity to expand, while the heavier properties collect at the bottom of the drum.

A vapor discharge pipe 49 leads laterally from the top of the drum and is supported on a standard 50 resting on top of the drum. This pipe is connected by means of suitable elbows with a pipe 51 which extends over the condenser box and is connected by means of elbows and couplings with a pipe 52 which is directed inwardly and connected to the lower portion of a tower 53. The pipe 52 and elbows connected thereto are supported by a standard 54 mounted on top of the condenser box. The tower is of the usual construction having a dished bottom 55 from which a drain pipe 56 extends. The light vapors rise to the top of the tower, while the heavy properties settle toward the bottom, due to the cooling action. The light vapors pass from the top of the tower into a depending pipe 57 which is connected at its lower end with a pipe 58 which in turn has connection with a manifold 59 extending across the inner end of the condenser box. The pipes 57 and 58 are supported by a standard 60 mounted on top of the condenser box.

In order that the tower may be removed it is provided at its lower end with a flanged ring 61 securely fastened thereto. The ring is secured to the top of the condenser box by stud bolts 62 passing therethrough, said bolts being suitably fastened to the top of said box. In order to sustain the load imposed by the tower I-beams 63, as is shown in Fig. 14, are placed transversely within the condenser box immediately under the top thereof. The pipes 49, 51, 52, 56, 57, and 58 are arranged so as to be disconnected and readily removed, together with the standards 50, 54 and 60. By this arrangement all super-structure above the condenser box and drum may be removed. It would

be possible to remove the manifold 59 but this will not be necessary as the height will be reduced sufficiently without such removal.

In order to promote combustion the still 6 is provided with a smoke stack 64. In order that the stack may be removed a channel ring 65 is countersunk in the top of the furnace and the lower end of the stack is telescoped thereinto as is shown in Fig. 13.

10 A flanged ring 66 is secured around the lower portion of the stack and fastened on the ring 65 by stud bolts 67. Suitable guys 68 extend from the upper portion of the stack and have their lower ends fastened 15 to the car in any approved manner. The stack may be removed by disconnecting the bolt 67 and the guys 68. Sufficient room is provided in the housing under the condenser box for storing the tower, stack and pipes 20 which are removed for transportation. It is estimated that the superstructure can be removed and replaced in a comparatively short time. It is pointed out that it might be possible to construct a refinery unit without a super-structure which would have to be removed and therefore the invention is 25 not to be limited to the same.

The light products conveyed to the manifold 59 are taken into the coils 25 and condensed. The liquid is discharged from the coils through a pipe 69. From the first unit gasoline may be obtained from the condenser coils. Two or more tube still units may be used in a plant and the arrangement on 30 the second unit will be slightly different from the first unit. However it will be necessary to mount a third pump 70 on No. 1 unit. This pump is connected with the lower portion of the expansion drum by a pipe 71. The pipe 56 is connected into pipe 71 and includes a valve 56'. By this arrangement the heavier products from the tower may be thus run back into the expansion drum or they may be carried 35 through the pump 70. A pipe 72 leads from the pump 70 to the second unit and includes a valve 72' aligned with the valves 36 and 38. The connections of the second unit are shown in Fig. 11. The pipe 50 72 is connected with a T 73 which is attached to the end of a pipe 74 which corresponds to the pipe 41 and which in turn is connected with an angular pipe 75 leading into the still 23 of the second unit. A T 55 76 is connected in the pipe 41 and has connection with a similar T 77 in the pipe 74 by means of a bypass pipe 78 as is indicated in Fig. 16. Of course the units must be placed parallel to make these connections. 60 By this arrangement it is possible to bypass the vapors back and forth through the pipe 78 from one tube still to the other or to cut off the bypassage by means of a valve 78' as is shown in Fig. 16.

65 The oil pumped through the pipe 72 en-

ters the still of the second unit and passes therefrom through the pipe 43. The second unit is otherwise constructed like the first unit except that the pumps 34 and 35 and their pipe connections are omitted. Kerosene may be discharged from the condenser box of the second unit, but it is to be understood that the units may be operated to produce various oils within their capacities.

The heavier products from the drum of 75 the second unit are pumped thru the pipe 72 thereof which latter is connected with a pipe 79 of a third unit which is known as a shell still unit. The pipe 79 includes a valve 79' and enters a shell still 80. The 80 still 80 is supported by means of lugs 81 upon side walls 82 which form a combustion chamber under the still. In order to give proper supporting strength, two of the lugs 81 are used on each side of the center 85 of the still as is shown in Fig. 4. In order to get sufficient heating surface and reduce the still to a minimum height, said still is given an elliptical shape as is shown in Fig. 8, and its bottom 83 is rolled on a 90 greater radius than its upper portion. This amplified heating surface gives a heating area and capacity which is the equivalent of that of a still of much greater diameter. The fire box and entire understructure is 95 also provided with the heat insulation layer 23'. On account of limited head room for a built up unit as required and yet to maintain sufficient room between the bottom of the still and the insulation layer to allow 100 for the proper height of combustion chamber it is necessary to provide a dome 84 on top of the still at the center thereof, into which the light vapors may rise directly 105 from the liquid in the still. In order that the dome may be removed it is provided with a screw threaded nipple 85 which as is shown in Fig. 12 screws into a flanged coupling 86 fastened on the still. The dome may be readily removed for transportation. 110

A vapor pipe 87 extends from the upper portion of the dome and is connected with an elbow joint 88 which in turn is connected with a pipe 89. The pipe 87 rests upon a standard 90 removably mounted on the still. The pipe 89 like the pipe 51 is connected to the pipe 52 of the tower 53 of the condenser means which is the same in this unit as in the others. A pipe 91 leads from the end of the still opposite the pipe 79 and includes a valve 91'. This pipe has connection with a four-way joint 92 connected in the pipe 79. The vapors passing out thru the pipe 91 may be by-passed back into the still by way of the pipe 79 and re-run if desired. 115 120 125

As shown in Figs. 1 and 2 the units may be connected in a train for transportation. In this train is shown, as typical, an engine and tender 93; a couple of gondola cars 94 for transporting tanks and pipes, a tool car 130

95, a shell still unit 21, two tube stills 20 and a private car 96. When train is moved over a level country which is free from bridges and overhead obstructions it may be possible 5 to leave the super-structure in position as shown in Figs. 1 and 2, but under most conditions it will be necessary to remove the same and store the parts in the housings formed under the condenser boxes. It will 10 be noted that elbow joints are used in many of the pipe connections and this is done to care for expansion.

In order to set up the refinery it would 15 of course be necessary to provide spur tracks as is shown in Fig. 3 where the three units are disposed on parallel spurs. A steam boiler 97 may be purchased in the field and connected with a steam pipe 98 having connection with the oil burners usually employed in the stills, which are also connected with a fuel pipe 99 extending from a fuel oil tank 100 which may be transported in one of the cars 94.

The pipes 69 from the condenser coils connect 20 with pipes 101 leading into a test house 102 which may either be erected in the field or transported. From the house pipe lines 103 lead to the storage tanks 104 which may be set upon arrival at the field. I have 25 shown tank cars 105 containing crude oil to be refined and connected with a pipe 106 which is connected with the pipe 36 in a suitable manner and pumped into the first tube still.

30 It is estimated that within three or four days after arrival at the field the plant will be ready for operation. This includes the placing of all super-structure, erection of tanks, heating plant and the connection of 35 all pipes and pipe lines. All connecting pipes such as 72, 78, 101, and 103 are cut to proper lengths so that pipe cutting and threading will not be necessary in the field.

Referring to Figs. 15 to 18 inclusive it 40 will be seen that the vapors and oils may be by-passed between the stills and re-run in many different ways. Fig. 16 illustrates the by-pass pipe 78 which connects the tube stills of units 1 and 2, whereby vapors may be by-passed direct from tube still to the other. In Fig. 17 I have shown a by-pass line 107 which is connected with the three-way joint 110 of No. 1 unit. This line is connected with a four-way joint 108 in the pipe 74 of 45 No. 2 unit and the joint 92 of No. 3 unit. By this line vapors may be passed from one unit to the other as desired. In Fig. 18 I have a pipe line 109 extending from the four-way joint 40' in the pipe 39 to a joint 50 111 in the pipe 71 of the No. 2 unit, whereby crude oil may be pumped to the pipe 79 of No. 3 still.

In the ordinary running of the plant it 55 is proposed to take off gasoline from the tube still of No. 1 unit, kerosene from No. 2 unit

and gas oil from unit No. 3; however the stills may be run by those skilled in the art to the best advantage and such oils taken off as the plant is capable of producing. The plant may consist of more units or less 70 units and may be used in connection with a heat exchanger or cracking unit, neither of which latter are shown. The pipe connections permit of great variation and the connection of the parts will largely depend upon the particular kind of crude oil to be refined and the products sought to be obtained. 75

What I claim, is:

1. In a portable refinery, the combination 80 of a plurality of independently portable units adapted to be assembled in a longitudinal series for transportation and to be disposed side by side for cooperative use, each unit comprising a connected oil still, cooling tower, and a condenser spaced from the still, and detachable pipe connections extending from one unit to the other, where- 85 the products may be successively passed to the units.

2. In a portable refinery, the combination 90 of a plurality of independently portable units adapted to be assembled in a longitudinal series for transportation and to be disposed parallel for cooperative use, each unit comprising a still and condenser in connected relation, and detachable pipe connections for uniting the units in parallel order and for by-passing the products not entering the condenser to a successive still unit. 95

3. In a portable refinery, the combination 100 of a plurality of independently portable units adapted to be assembled in a longitudinal series for transportation and to be disposed parallel for cooperative use, each unit comprising a still and condenser in connected relation, detachable pipe connections for uniting the units in parallel order, and separate pumps upon one of the units 105 for supplying liquid thereto and for pumping liquid through said connections from one unit to another. 110

4. In a portable refinery, the combination 115 of a plurality of independently portable units adapted to be assembled in a longitudinal series for transportation and to be disposed parallel for cooperative use, said units comprising a first unit including a still, an expansion drum connected thereto, a tower connected to the drum, and a condenser connected with the tower; and a sec- 120 ond unit including a still, a tower connected thereto, and a condenser connected with the tower; and detachable pipe connections for feeding from the tower of the first unit to the still of the second unit. 125

5. A portable refinery unit including a mobile support, a still mounted at one end thereof, a smoke stack having a removable connection with said still, a condenser mounted upon the other end of the support, 130

- 6 a cooling tower having a removable connection with the upper portion of said condenser, removable pipe connections between the still and the tower, and removable pipe connections between the tower and condenser.
- 10 6. A portable refinery unit including a mobile support, a still mounted at one end thereof, a smoke stack having a removable telescoping connection with said still, a condenser mounted upon the other end of said support, a cooling tower having a securing flange removably mounted upon the top of the condenser, removable pipe connections between the still and tower, and removable pipe connections between the tower and condenser. 25
- 15 7. A portable refinery unit including a mobile support, a still mounted at one end thereof, a smoke stack having a removable telescoping connection with said still, a condenser mounted upon the other end of said support, a cooling tower having a securing flange removably mounted upon the top of the condenser, removable pipe connections between the still and tower, and removable pipe connections between the tower and condenser. 30
- 20 8. In a portable refinery unit, a wheeled support, a still mounted thereon, a condenser box upon the support, coils within said box, means traversing the box at the ends of the coils to prevent longitudinal shifting thereof, and transverse supports intermediate the coils to permit expansion and contraction thereof. 35

In testimony whereof I affix my signature.
THOMAS W. SOWELL.
